(57) **CLAIM**

The ornamental design for an independently movable foil swim fin, as shown and described.

DESCRIPTION

FIG. 1 is a top perspective view of an independently movable foil swim fin showing my new design;

FIG. 2 is a right side elevational view thereof, the left side elevational view being a mirror image of that shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a top perspective view of a second embodiment of the independently movable foil swim fin;

FIG. 8 is a right side elevational view of FIG. 7, the left side elevational view being a mirror image of that shown;

FIG. 9 is a front elevational view of FIG. 7;

FIG. 10 is a rear elevational view of FIG. 7;

FIG. 11 is a top plan view of FIG. 7; and,

FIG. 12 is a bottom plan view of FIG. 7.
